DESIGN FOR A PASTEURIZER OR SIMILAR ARTICLE

James L. Herold, St. Louis, and Frederick W. Wehmiller, Ladue, Mo., assignors to Barry-Wehmiller Machinery Company, St. Louis, Mo., a corporation of Missouri

Application May 18, 1940, Serial No. 92,456

Term of patent 14 years

To all whom it may concern:

Be it known that we, James L. Herold and Frederick W. Wehmiller, citizens of the United States of America and residents of the city of St. Louis and State of Missouri, and the city of Ladue, in the county of St. Louis and State of Missouri, respectively, have invented a new, original, and ornamental Design for a Pasteurizer or Similar Article, of which the following is a specification, reference being had to the accompanying drawing, forming part thereof.

Fig. 1 is a perspective view of a pasteurizer or

similar article showing our new design. The side and end of the article not shown in Fig. 1, are substantially like the side and end shown therein.

Fig. 2 is a top view of the article shown in Fig. 1.

We claim:

The ornamental design for a pasteurizer or similar article, substantially as shown and described.

JAMES L. HEROLD.
FREDERICK W. WEHMILLER.
